UNITED STATES PATENT OFFICE

2,554,496

SAFETY DEVICE

Aylmer H. Maude, Niagara Falls, N. Y., assignor
to Hooker Electrochemical Company, Niagara
Falls, N. Y., a corporation of New York

Application April 19, 1947, Serial No. 742,602

1 Claim. (Cl. 23—252)

2

1 My invention relates to apparatus for controlling the pressure of gases supplied to reaction chambers, as for example, when they are supplied through calibrated orifices, and it is desirable that the supply should be in accurately controlled proportions; and also for safeguarding reaction chambers or apparatus associated therewith against explosion or other complications in the event of the supply of one of the gases being cut off, interrupting the reaction, and the other gas continuing to flow, and supply of the interrupted gas being then resumed, automatically or inadvertently, particularly under reacting conditions.

Examples of gases that are commonly reacted are chlorine with hydrogen, methane, etc. These are burned together in burners located in combustion chambers. Other gas phase reactions are chlorine with carbon monoxide, and hydrogen chloride with acetylene, etc. These are catalytic reactions.

In each of these cases products of reaction are valuable chemical compounds and either collected or stored or passed immediately to a second reaction. An illustration of a product produced in a burner which may be immediately passed to a second reaction is combustion of chlorine with hydrogen and reaction of the resulting hydrogen chloride with acetylene.

When one of the gases fails, it is practically impossible to shut off the other in less than a fraction of a second, during which time an objectionable and perhaps dangerous quantity of the other gas may have flowed into the reaction chamber. Therefore, rather than try to shut off the other, I have found it better to provide that one of the gases shall always flow for a time after the other, so that there shall be no uncertainty as to which gas shall fill the reaction chamber after any accidental shut-down. Each particular case therefore presents a different safety problem. Thus in the case of the chlorine-hydrogen burner, if the product is to be absorbed in water, it may be desirable to leave the combustion chamber filled with chlorine, which does not form an explosive mixture with air; or on the other hand, if the products of the reaction are to be passed directly to a reaction with acetylene in a closed system, it may be better to leave the combustion chamber filled with hydrogen, which does not react with acetylene.

For purpose of illustration, I will describe my apparatus as applied to the burning of chlorine and hydrogen together, on the assumption that it is desired always to leave the combustion cham-

ber free from hydrogen, in case of interruption of either gas.

In Patent No. 2,295,591, issued to me September 15, 1942, there are illustrated a burner and combustion chamber for burning chlorine and hydrogen together, the gases being supplied through calibrated orifices. In Patents Nos. 2,366,669 and 2,366,670, issued to me January 2, 1945, there are illustrated a burner and combustion chamber of an improved type, intended for the same purpose. In each of these, provision is made for relieving pressure in the combustion chamber in case of explosion therein, and thereby rendering the explosion relatively harmless. The present invention goes further back, and aims to minimize the likelihood of conditions arising that could possibly result in explosion.

In carrying out my invention, I utilize a gasometer and calibrated orifice to control the supply of each gas to the burner. The previously dried gases are supplied to the gasometers, from a source such as a circuit of electrolytic cells, under pressure sufficient to lift the gasometer bell. The pressure in a gasometer bell increases as the gasometer rises from the empty to the full position. Therefore, in order to hold it as nearly as possible constant, I provide a throttling valve in the infeed to each bell and mechanism by which each valve is closed progressively as the bell rises. Thus the travel of the bell is held to narrow limits and the pressure upon its orifice kept nearly constant.

In addition to the aforementioned throttling valves, I provide a shut-off valve controlling exit of hydrogen from the hydrogen gasometer to its orifice and another shut-off valve controlling admission of chlorine to the chlorine gasometer. These shut-off valves are normally locked in wide open position, but when the locking mechanism is tripped, each of these shut-off valves instantly closes tightly. The shut-off valve controlling exit of hydrogen from the hydrogen gasometer is tripped by mechanism actuated by the chlorine gasometer when the latter is in empty position. The shut-off valve controlling admission of chlorine to the chlorine gasometer is tripped by mechanism actuated by the hydrogen gasometer when the latter is in empty position. Thus, failure of the chlorine supply to the burner instantly cuts off the hydrogen, but failure of the hydrogen supply permits the contents of the chlorine gasometer to be discharged through the burner into the combustion chamber. Failure of either gas therefore shuts off both, but always leaves the combustion chamber free of hydrogen.

Referring to the drawings:

Fig. 1 is a plan view of the assembly of gasometers, piping, valves, etc.

Fig. 2 is a front elevational view of the same, the burner and combustion chamber being indicated diagrammatically.

Fig. 3 is an elevational view of a portion of the assembly, in section along the line *a—a* and as seen from the top of Fig. 1.

Fig. 4 is an end elevational view of a portion of the assembly, as seen from the top in Fig. 1, with the portion of the assembly illustrated in Fig. 3 removed, for simplicity, the gasometer being shown in section.

Fig. 5 is an elevational view of one of the shut-off valves, with its locking and tripping mechanism, to an enlarged scale.

Fig. 6 is a plan view of the same.

Fig. 7 is an elevational detail of the locking mechanism to a still larger scale.

Fig. 8 is an elevational view of the shut-off valve and trip mechanism to a reduced scale, showing the valve tripped and closed.

Fig. 9 is a detail to the scale of Figs. 5 and 6, of the sleeve which actuates the arm of the throttling valve.

Figs. 5 to 9 serve to illustrate valves associated with both the hydrogen and chlorine systems and are therefore provided with a due set of reference numerals, those enclosed in parentheses referring to the chlorine system.

Referring to the figures:

1 is the hydrogen gasometer and 2 the chlorine gasometer.

These gasometers comprise respectively tanks 3, 4, bells 5, 6 adapted to telescope with tanks 3, 4 and suspended from cable 7, 8 which pass over pulleys 9, 10 and 11, 12 respectively.

From cable 7 is suspended a counterweight comprising bar 13 and sleeve 14. Sleeve 14 slides freely upon standpipe 15, which serves as a guide therefor, as bell 5 rises and falls. Similarly, from cable 8 is suspended a counterweight comprising bar 16, and sleeve 17, sliding freely on standpipe 18.

For chlorine and hydrogen, the sealing liquid in the tank may be concentrated sulphuric acid. It should of course stand at such a level that the bottoms of the bells are always submerged. The bells are weighted as indicated at 19 (Fig. 4) and the counterweights are only sufficient to maintain the cables under tension; so that the gas in the bells is under a moderate pressure.

Admission of hydrogen to gasometer 1 is by means of pipe 20. From bell 1 the hydrogen is conducted through flame arrester 21, pipe 22, meter 23 and pipe 24 to the burner (Fig. 2). Bypass 25 and hand operated valve 26 are provided to enable the hydrogen to be by-passed around meter 23.

Admission of chlorine to gasometer 2 is by means of pipe 27. From gasometer 2 the chlorine is conducted through pipe 28 to the burner.

The hydrogen and chlorine may be derived from a circuit of electrolytic cells (not shown) if subsequently dried and brought under a suitable pressure. Hand operated valves 29 and 30 (Fig. 4) are provided in pipes 20 and 27, respectively for shutting off the supply of these gases in emergency.

In the vertical leg of pipe 20 is provided throttling valve 31, of the plug cock type. Valve 31 is actuated through arm 32. Arm 32 is lifted, opening valve 31, by sliding engagement with sleeve 33, pivoted upon pin 34, projecting from sleeve 14.

as may be seen in Figs. 4 and 9. It is lowered by weight 35.

In the vertical leg of pipe 27 is provided throttling valve 36, likewise of the plug cock type. 5 Valve 36 is actuated through arm 37. Arm 37 is raised, opening valve 36, by sliding engagement with sleeve 38, pivoted upon pin 39, projecting from sleeve 17, as may be seen in Figs. 3 and 9. It is lowered by weight 40.

Falling movement of sleeves 14 and 17, corresponding to rising motion of bells 1 and 2, therefore increases the throttling effect of valves 31 and 36 respectively, and vice versa. The setting of these valves is such that when the bells are in normal position, about three quarters full, they are about half open. As the bells rise, the valves are progressively closed, checking further rise. Conversely, as the bells fall the valves open wider, checking further fall. These throttling valves may be hand adjusted by mechanism indicated at 41, Fig. 2, to give the desired settling.

Thus the bells are held to a very limited travel and the pressure of the gas delivered by them is kept substantially constant.

25 However, when the bells reach the empty position, arms 32 (37) slip completely out of their respective sleeves 33 (38). Under the action of weights 35 (40), these arms then instantly fall and shut off pipes 20 and 27, respectively. Thus the throttling valves also become shut-off valves, when their respective bells are empty. If the supply of gas should then be resumed, none can flow into its bell until the valve has been reopened by hand.

26 In the vertical leg of pipe 24, is provided automatic shut-off valve 42. Valve 42 is actuated through arm 43 by weight 44. It is normally locked in open position by engagement of lug 45, projecting from arm 43, with lug 46, projecting from trigger 47, which is pivoted at 48 upon stand pipe 49. Trigger 47, is adapted to be tripped by pin 50 projecting from sleeve 17.

This mechanism is more clearly illustrated in Figs. 5 to 8. Thus shut-off valve 42, in the exit for hydrogen from bell 1, is tripped and the supply of hydrogen to the burner instantly cut off, as illustrated in Fig. 8, when pin 59 lifts arm 41. But sleeve 17 and pin 50 are under control of bell 2; hence, flow of hydrogen from bell 1 to the burner is cut off when chlorine bell 2 reaches its lowermost position, i. e., when the supply of chlorine fails.

55 In the vertical leg of pipe 27, is provided automatic shut-off valve 51. Valve 51 is actuated through arm 52 by weight 53. It is normally locked in open position by engagement of lug 54, projecting from arm 52, with lug 55, projecting from trigger 56, which is pivoted at 57 upon stand pipe 58. Trigger 56 is adapted to be tripped by pin 59, projecting from sleeve 14. Thus, shut-off valve 51, in the inlet for chlorine to bell 2, is tripped, and the admission of chlorine to bell 2 instantly cut off, when pin 59 lifts trigger 56. But sleeve 14 and pin 59 are under control of bell 1; hence, flow of chlorine to bell 2 is cut off when bell 1 reaches its lowermost position, i. e., when the hydrogen supply to the burner fails. Any residual chlorine in bell 2 is, however, not prevented from flowing to the burner, until bell 2 is likewise empty.

60 The burner and combustion chamber are indicated at 60 and 61, Fig. 4, respectively, and the calibrated orifices at 62, 63.

65 It should be noted that shut-off valve 42 is located in the outlet from bell 1 to the burner.

whereas shut-off valve 51 is located in the inlet from the source of chlorine to bell 2. There is no shut-off valve in the outlet from bell 2 to the burner. Hence, the hydrogen flow to the burner is always cut off before the chlorine flow is cut off, and when the hydrogen is cut off the chlorine continues to flow long enough to consume any hydrogen in the pipe leading to the burner. The combustion chamber can therefore never be left filled with hydrogen or an explosive mixture of hydrogen and chlorine, but is always left filled with chlorine or hydrogen chloride.

It should also be noted that when the chlorine bell has emptied itself it trips the hydrogen shut-off valve. Failure of either gas, which of course extinguishes the burner flame, therefore leaves both shut-off valves closed, as well as both throttling valves, and resumption of normal operation is under full manual control. This involves first seeing that both gasometers are supplied with gas, opening the throttling valves, opening the chlorine shut-off valve and locking it in open position, and finally, with an ignition torch playing upon the burner, opening the hydrogen shut-off valve and locking it open.

In like manner, if preferred, the apparatus may be constructed so that in the event of failure of either gas the combustion chamber will always be left filled with hydrogen, or a mixture of hydrogen and hydrogen chloride, and substantially free from chlorine.

In the combining of hydrogen chloride with acetylene to produce vinyl chloride, it is generally preferred to adapt the apparatus to prevent the reactor from becoming filled with acetylene. On the other hand, in burning chlorine with methane, or combining it with carbon monoxide, it is generally preferred to leave the chamber filled with chlorine rather than with the other gas.

I claim as my invention:

In apparatus for supplying two reactable gases A and B to a reaction chamber, which apparatus includes a pressure control chamber for each gas, an inlet conduit for each gas to its respective pressure control chamber and an outlet conduit for each gas from its respective pressure control chamber to said reaction chamber, a vertically movable bell in each pressure control chamber and a counterweight therefor, and throttling valves controlling the admission of gas into said pressure chambers and proportioning means maintaining them in predetermined proportions so long as the supply of each gas remains unimpaired, the improvement in safety shut-off means therefor comprising: a shut-off valve in the inlet conduit for gas A; a shut-off valve in the outlet conduit of gas B; a weighted arm affixed to each of said valves in such position that movement thereof in response to said weights will

fully and immediately close said respective valves; a sidewardly extending lug on each of said arms; support means adjacent each counterweight; a trigger on each support means, each trigger having two legs perpendicularly with respect to each other and positioned with one arm substantially vertically arranged and the other substantially horizontal, said triggers each being pivotally mounted at the lower extremity of its vertically positioned leg on said support means and having a lug at the intersection of each of said legs normally engaging the lugs on each of said respective arms for holding same in raised, or valve-open, position against said weights, and having their respective horizontal legs extending adjacent each of said counterweights; pins extending from each of said counterweights engageable with said horizontal trigger legs when the counterweights are raised beyond certain predetermined positions by which to move said horizontal legs on their respective pivot points and disengage said respective lugs and release said arms, the arms controlling gas A being associated with the counterweight of the gas B pressure chamber and the arm controlling gas B being associated with the counterweight of the gas A pressure chamber; and said proportioning means comprising means constantly urging said throttling valves to fully closed position, releasable means connected with said counterweights normally holding each of said valves independently open and movable with movement of said counterweights and each released when the counterweight to which it is connected moves past said certain predetermined positions, whereby to close substantially instantaneously the throttle valve associated with whichever gas is controlled by the pressure control chamber whose counterweight has so moved past such predetermined position; whereby falling of gas pressure in the pressure chamber for either gas and the consequent raising of the corresponding counterweight beyond a predetermined point will effect substantially instantaneous closing of the shut-off valve controlling the other gas and the reaction chamber will, regardless of which gas source has failed, be left with a concentration of gas A substantially in excess of the concentration utilized for reaction purposes.
